UNITED STATES PATENT OFFICE.

LUDWIG MINLOS, OF COLOGNE-EHRENFELD, GERMANY.

APPARATUS FOR DELIVERING LIQUIDS.

978,047.

Specification of Letters Patent.

Patented Dec. 6, 1910.

Application filed November 1, 1909. Serial No. 525,688.

To all whom it may concern:

Be it known that I, LUDWIG MINLOS, manufacturer, a subject of the Emperor of Russia, residing at No. 118 Geisselstrasse, 5 Cologne-Ehrenfeld, Germany, have invented new and useful Improvements in Apparatus for Delivering Liquids, of which the following is a specification.

The present invention relates to an apparatus for dispensing or delivering liquids, such as disinfectants, detergents, perfumes, medicines, etc.

The new apparatus is not designed merely for dispensing relatively large quantities 15 of liquids, but is adapted for dispensing small, and even very small, quantities, such as is requisite in the case for instance of medicines and perfumes. The apparatus can also be employed for corrosive fluids 20 and for such as throw down a sediment.

It consists of a vessel, which may advantageously be connected at the bottom of the reservoir which contains the supply of liquid, the communication between the two 25 being controlled by a valve. The latter is so connected with the liquid-exit and air-inlet that alternate opening and closing result, whence premature outflow of the liquid is prevented, and steady flow of the delivered liquid in a continuous current insured. For this purpose the body of the 30 valve is linked to a plate sliding over the exit of the vessel, and the link at the same time operates the lever which actuates the valve of the air-inlet, so that the liquid-exit and air-inlet are opened and closed simultaneously.

In the drawing two practical embodiments 35 of the invention are shown.

Figure 1 is a vertical section of a reservoir fitted with the new device. Fig. 2 is a vertical section showing a modification of the device, on a larger scale.

The bottom *b* of the reservoir *a* for the 45 liquid inclines slightly in the direction of the exit, and the top of the reservoir is closed by a cover *c*. A liquid-gage *d* may with advantage be provided at one side of the reservoir, in order that the height of the liquid may be readily ascertained. Near 50 the lowest part of the bottom *b* there is provided the exit *e*, controlled by a valve *f*. The latter is drawn to its seat by the action of a spiral spring *g*, held by a plate *h* secured to the bottom *b* with the aid of supports *i*. The valve *f* is carried by a rod *j*,

which passes centrally through it and terminates in a handle *k*. The rod *j* is suitably packed at the place where it passes through the wall of the vessel *m*. The latter may be 60 of any suitable shape and size, and is preferably secured direct to the underside of the reservoir bottom *b*. *n* is an outlet pipe from the vessel *m*, while *o* is an air-inlet pipe. The mouths of the pipes *n*, *o* are controlled 65 by suitable valves, which are connected with the valve *f*. In the embodiment illustrated in Fig. 1 this connection is effected by means of a bar *p*, pivoted at one end to the valve *f*, and at the other end to the slide *q* 70 which controls the mouth of the pipe *n*. To insure close shutting of the sliding-valve *q*, a fillet *u* preferably presenting lateral guide-pieces, is furnished, below which the slide passes. The air-inlet *o* is controlled 75 by means of a double-armed lever *r*, fulcrumed to a bracket *t*, pendent from the bottom *b*. The upper end of the lever *r* carries the valve, consisting for example of a rubber ball *s*, while the lower end projects through an aperture in the bar *p* and is thus actuated on motion of the latter. Any other suitable manner of connecting the lever *r* and bar *p* may, however, be adopted. 85

The modification shown in Fig. 2 differs from the construction above described only in details. The tension-spring *g* is replaced by a compression-spring, which rests upon a plate *h* secured by means of arms *i* to the bottom *b* of the reservoir. The slide *q*, linked to the valve *f* by means of the bar *p*, moves upon a smooth surface, between slide-bars *v* or fillets formed with the guide *u*, whereby a close joint is insured at the 90 mouth of the pipe *n* even should deposits form on the surface below the slide, and which would otherwise force it upward. 95

The operation of the apparatus is as follows: When a quantity of liquid is to be delivered from the reservoir *a*, the valve *f* must be open against the action of its spring *g*, by pulling the handle *k* of the rod *j*. The bar *p* will be actuated simultaneously, and the slide *q* thus pushed over 100 the base of the vessel, below the projecting flange of the part *u*, so that the mouth of the pipe *n* is tightly closed. The bar *p* in moving will also shift the lower end 105 of the lever *r*, until the valve *s* at the opposite end of the latter closes the mouth of the air-pipe *o*. Through the aperture *e* 110

liquid will enter the vessel *m*, until the latter is quite full; its escape is prevented, since the mouths of the pipes *n*, *o* are closed. If, now, the handle *k* is released the valve *f* will close automatically, swing to the action of the spring *g*, and the mouth of the pipes *n*, *o* will be opened simultaneously. The liquid in the vessel *m* will thus flow out in a thin, uniform current.

10 The new apparatus can be employed for delivering or dispensing liquids of all descriptions, such as disinfectants, detergents, perfumes, medicines, etc., in any desired quantity. The shape of the vessel *m*, the 15 valve *f* and the other valves and mechanisms connecting the same can naturally be varied.

Having thus described my invention, I declare that what I claim is:—

1. A liquid reservoir, a delivering-vessel 20 communicating therewith and having a liquid-outlet and an air-inlet, a valve controlling the passage of the liquid between the two receptacles, a slide controlling the liquid outlet, and linked to said valve, and 25 a double-armed pivotal lever whose one end is engaged by the link connecting the first

said valve and slide, while the other end carries a valve adapted to control said air-inlet, substantially as described.

2. A liquid reservoir, a liquid delivery 30 vessel communicating therewith and having a liquid outlet and an air-inlet, a spring actuated valve controlling the passage of the liquid, between the two vessels, a sliding valve, for controlling the liquid outlet, 35 connected to and operated from the said spring actuated valve, slide bars for guiding the sliding valve, and a double armed pivotal lever whose one end is connected with and operated by the link connecting the said 40 valves while the other end carries a valve adapted to control said air inlet, substantially as described.

In witness whereof I have hereunto signed my name at Cologne this 8th day of Octo- 45 ber, 1909, in the presence of two subscribing witnesses.

LUDWIG MINLOS.
